CARTON

William P. Frankenstein, Cincinnati, Ohio

Application March 19, 1948, Serial No. 15,871

15 Claims. (Cl. 229—31)

1

This invention relates to improvements in cartons and particularly to improvements in cartons or boxes of the knocked down variety formed from a single blank of card or paper board material having, when erected, a platform intermediate the height of the walls.

Foldable or knocked down boxes or cartons having a partition or platform intermediate the upper and lower ends of the walls are not necessarily new with this application except to the extent of improved construction and added rigidity and strength together with ease of operation in the setting up of the box or carton from the said knocked down position.

The primary object of the present invention is the provision of an improved knocked down box or carton that can be erected from the flat to provide a platform for the box extending transversely thereof between the walls and intermediate the height of said walls.

Another object of this invention is the provision of a knocked down box or carton that can be readily set up with a minimum of effort for automatically positioning the walls of the box or carton normal to the base and automatically positioning and locking a platform upwardly of the base.

Another object of this invention is the provision of a box or carton that is automatically folded to its knocked down position subsequent to the blanking out of the blank from which the carton is subsequently erected, said folding being done with subsequent erection in mind whereby the box or carton can be readily erected when desired for use.

A further object of the present invention is the provision of a box or carton having a platform upwardly of its bottom necessitating folding of the blank to have several portions thereof superimposed on one another with portions of said superimposed layers adhesively connected to one another and wherein the blank is so designed that the adhesively attached parts are subjected to equal and proper pressures in effecting their attachment.

A still further object of the present invention is the provision of a carton or box formed from a single blank and having walls and a platform in which the several walls and members thereof as well as the platform interengage with one another in holding the walls in assembled and erected positions.

Other objects and advantages of the present invention should be readily apparent by reference to the following specification considered in

2

conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a plan view of a blank with a part thereof folded from which a carton embodying the principles of the present invention may be erected.

Fig. 2 is a transverse sectional view of the blank of Fig. 1 when in its folded position and as shipped to the user.

Fig. 3 is a perspective view of a partially erected carton erected from the blank of Figs. 1 and 2.

Fig. 4 is a transverse sectional view through the carton of Fig. 3 as seen from line 4—4 on said Fig. 3.

Fig. 5 is a longitudinal sectional view through the carton of Fig. 3 as seen from line 5—5 on said Fig. 3.

Fig. 6 is a plan view of a blank similar to Fig. 1 showing a modification therein but embodying the principles of the present invention.

Fig. 7 is a transverse sectional view through the blank of Fig. 6 in its final folded position as shipped to the user.

Fig. 8 is a partially erected carton or box from the blanks of Figs. 6 and 7.

Fig. 9 is a longitudinal sectional view of the carton of Fig. 8 as seen from line 9—9 on said Fig. 8.

Fig. 10 is a transverse sectional view through the carton of Fig. 8 as seen from line 10—10 on said Fig. 8.

Fig. 11 is a plan view similar to Fig. 1 of a blank embodying modifications therein for forming a modified carton.

Fig. 12 is a transverse sectional view through the folded carton blank of Fig. 11 from which the carton is readily erected.

Fig. 13 is a perspective view of a partially erected carton from the blank of Figs. 11 and 12.

Fig. 14 is a longitudinal sectional view of the carton of Fig. 13 as seen from line 14—14 on said Fig. 13.

Fig. 15 is a transverse sectional view of the erected carton of Fig. 13 as seen from line 15—15 on said Fig. 13.

Fig. 16 is a plan view similar to Fig. 1 of a blank showing further modifications therein for

forming a carton embodying the principles of the present invention.

Fig. 17 is a transverse sectional view of the knocked down or folded carton as shipped to the user and involving the blank of Fig. 16.

Fig. 18 is a perspective view of a partially erected carton from the blank of Figs. 16 and 17.

Fig. 19 is a top plan view of the blank of Figs. 16 and 17 in process of being erected.

Fig. 20 is a transverse sectional view of the carton of Fig. 19 in the process of erection as seen from line 20—20 on said Fig. 19.

Fig. 21 is a plan view, similar to Fig. 1, of a blank embodying modifications for providing a carton of a modified construction embodying the principles of the present invention.

Fig. 22 is a transverse sectional view through the folded blank of Fig. 21 in the condition in which it is shipped to the user.

Fig. 23 is a perspective sectional view of a carton erected from the blank of Figs. 21 and 22.

Fig. 24 is a longitudinal sectional view through the carton of Fig. 23 as seen from line 24—24 on said Fig. 23.

Throughout the several views of the drawings similar reference characters are employed to denote the same or similar parts.

The carton or box blank of Fig. 1 comprises a panel 25 having its sides or edges defined by score or fold lines 26, 27, 28 and 29. For the purposes of description and identification the score or fold lines 27 and 29 will be referred to as the sides while the score or fold lines 26 and 28 will be referred to as the ends but it is to be understood that these terms are interchangeable. The bottom panel 25 has connected to its one side an extension 30 which in the erected carton forms one side wall and the carton platform while the bottom 25 has connected to its other side an extension 31 which forms in the erected carton a second side wall.

The extension 30 is longitudinally divided by parallel score or fold lines 32, 33, 34, 35, 36 and 37 into panels 38, 39, 40, 41, 42, 43 and 44. In the erected carton the panel 38 forms one side wall outer wall member having its ends defined by score or fold lines 45 and 46 which are in substantial alignment with the bottom panel end score or fold lines 26 and 28. The panel 39 has its ends defined by cut lines 47 and 48 and constitutes in the erected carton one side wall top wall member and is positioned substantially parallel with the carton bottom panel 25. The panel 40 in the erected carton forms the side wall inner wall member and has its ends defined by score or fold lines 49 and 50 which integrally hinged connect to said panel 40 flaps 51 and 52. The flaps 51 and 52 are in turn, each, divided by a score or fold line 53 which, respectively, integrally hinged connect to the flaps 51 and 52 spacer tabs 54 and 55. In the erected carton the panel 41 forms the platform upwardly spaced from the bottom panel 25 and has its ends defined by score or fold lines 56 and 57 which integrally hinged connect thereto brace flaps 58 and 59. The panel 41 is illustrated as having within its borders, in phantom lines 60, a cutout which is provided, as is usual practice, for receiving the body portion of an article to be displayed and shipped therein.

In the erected carton the panel 42 forms a support for the longitudinal edge of the platform panel 40 and has its sides defined by cut lines which are inwardly spaced from the platform ends or score or fold lines 56 and 57 an amount equal to the thickness of the box material since 75

this brace depends between said platform end and the end walls. The panel 43 constitutes in the erected carton a sub-bottom and is placed in face contact with the carton main bottom panel 25 for thereby strengthening said carton bottom. The panel 44 in the erected carton forms in part a brace for the other longitudinal edge of the platform panel 41 and in part a glue flap whereby the panels are hinged to one another for subsequent erection in spacing the platform 41 from the carton bottom panels 25 and 43. In the final position of the panel 44 it constitutes a portion of the side wall inner wall member along with the panel 40 and is provided inwardly thereof and adjacent its ends with notches 61 and 62 which are superimposed on elongated apertures 63 and 64 in the panel 40 and wherein said elongated apertures 63 and 64 are formed inwardly, in the erected carton, upwardly, of the score or fold line 34 at one side of the panel 40.

The side wall extension 31, similar to the side wall and platform extension 30, is longitudinally divided by score or fold lines 65 and 66 for thereby forming in said extension 31 between the score or fold line 29 and the end of said extension, panels 67, 68 and 69. In the erected carton the panel 67 constitutes the carton second side wall outer wall member and has its ends defined by score or fold lines 70 and 71 which are in alignment with the bottom panel end scores 26 and 28. The panel 68 in the erected carton forms the said second side wall top wall member and has its ends defined by cut lines 72 and 73. The panel 69, in the erected carton, forms the second side wall inner wall member having its ends for the major portion thereof defined by score or fold lines 74 and 75 which integrally hinged connect thereto tucking flaps 76 and 77. Said tucking flaps 76 and 77 are in turn, each, divided by score or fold lines 78 which respectively hinged connect with the tucking flaps 76 and 77 spacer tabs 79 and 80. The portion of the panel 69 beyond the tucking flaps 76 and 77 act as a glue flap in hinged connecting the parts to one another. The second side wall inner wall member or panel 69, similar to the panel 40, is provided with elongated apertures 98 and 99 inwardly of its end scores 74 and 75 with said apertures 98 and 99 extending inwardly, in the erected carton, upwardly, of the portion of said panel which constitutes the glue flap.

The carton bottom panel 25 has hinged connect thereto through its end scores 26 and 28 extensions 81 and 82 which in the erected carton form the end walls and since said extensions 81 and 82 are substantial duplicates of one another it is deemed sufficient if but one of them be described in detail.

Accordingly, extension 81 is provided longitudinally thereof with a plurality of score or fold lines 83, 84 and 85 thereby providing in said extension between the score or fold line 26 and its end, panels 86, 87, 88 and 89.

In the erected carton the panel 86 forms the end wall outer wall member having its ends defined by score or fold lines 90 and 91 which are in alignment with the carton bottom panel side scores 27 and 29. The panel 87 in the erected carton forms the end wall top wall member with its ends defined by cut lines in alignment with the score or fold lines 90 and 91, while the panel 88 forms the end wall inner wall member. Since the end wall inner wall member, in the erected carton, is positioned between the side walls inner wall members its length is less than that of the end wall outer wall member by so much as con-

stitutes the combined widths of side walls top wall members or panels 39 and 68. The said end wall inner wall member or panel 88 has its ends, in the main, defined by score or fold lines 92 and 93 which hingedly connect thereto spacer tabs 94 and 95. Beyond the said score or fold lines 92 and 93 the panel 88 has projecting therefrom locking lugs 96 and 97 which in the erected carton, respectively, enter the side walls opposed elongated apertures 63 and 64 and 98 and 99.

The side and end walls outer wall members have between their adjacent ends similar corner pieces 103 each of which is divided by a score or fold line 104 that extends diagonally thereof from its innermost corner to its outermost corner. Said corner pieces 103 are known as a bellow corner having the portions thereof on opposite sides of its score or fold line 104 folded on one another in the erected carton as will presently be made clear.

The blank after being cut and scored as just described is provided with a band of adhesive 100 on the panel 40 whereupon the portion of the extension 30 outwardly of the score or fold line 36 is folded on said score or fold line 36 to bring a portion of the panel 44 into engagement with said adhesive. Adhesive is then applied to the now exposed surface of the panel 43, as seen in Fig. 1, or, adhesive, indicated by reference numeral 101, is applied to the carton bottom panel 25 whereupon the extension 30 is folded on the score or fold line 32 thereby bringing the panel 43 and panel 25 into face contact. This folding now exposes the unexposed face of panel 42, as seen in Fig. 1, and to which now exposed face of panel 42 is applied a band of adhesive or the adhesive may be applied to the portion of the panel 69 which constitutes the glue flap thereof by applying same to its under surface illustrated at 102. At this time the blank extension 31 is folded on the score or fold line 66 bringing the under surface, as seen in Fig. 1, of panel 69 as the exposed surface whereupon the said extension 31 is again folded on the score or fold line 29 thereby bringing the panels 42 and 69 into face contact with the adhesive 102 therebetween. The folded blank is now in the position illustrated in cross-section in Fig. 2 and is subjected to pressure for permanently adhesively uniting the parts to one another. The blank is in its folded or knocked down position in which it is shipped to the user for subsequent erection and use.

From the foregoing and as disclosed in the drawings it will be noted that the first side wall inner wall member or panel 40 is of less depth than the side wall outer member or panel 38 while the corresponding panels 69 and 67 which respectively form the inner and outer wall members of the second side wall are of substantially equal depth. Also it will be noted that the end walls inner wall members or panels 88 are of less depth than their respective outer wall members or panels 86. The supplementary bottom or panel 43 while of substantially the same length as the main bottom panel 25 is of less width than said main bottom panel 25 by so much as equals the combined widths of the side walls top walls or panels 39 and 68 while the platform or panel 41 is substantially equal to the length and width of the supplementary bottom panel 43. The reasons for these variations in sizes is readily apparent from the disclosure in Figs. 3, 4 and 5 and will presently be made clear.

The user upon desiring to set up the box or

carton utilizes the folded blank as received by him and as seen in Fig. 2 and proceeds to lift the side walls from their flat or collapsed positions which, in effect, means merely raising the side walls outer wall members or panels 38 and 67 to be normal to the bottom panel 25.

The raising of the side walls outer wall members automatically sets up the said side walls and platform to the positions illustrated in Fig. 4 thereby disposing the side walls top wall members or panels 39 and 68 to be parallel with the bottom panel and with the side walls inner and outer wall members parallel to one another and normal to the carton bottom panel. The spacer-glue flap or panel 44 along with the inner wall member or panel 40 extends from the said bottom 25 to the top wall member. The inner wall member or panel 69 likewise extends from the carton bottom panel 25 to the top wall member 68 and has secured to the glue flap portion thereof of the platform spacer or panel 42. From this it will be seen that the platform or panel 40 is positively anchored along its sides against movement within the box or carton either upwardly or downwardly.

The user now downwardly turns the spacer flaps 58 and 59 to support the ends of the platform or panel 41. The end wall extensions are then folded on their various score lines after first upwardly, from the position shown in Fig. 1, bending the end wall inner wall member spacer flaps 94, 95 and 89 to be normal to the extension. It is of course understood that the tucking flaps 51, 52, 76 and 77 were folded to be transversely of the carton and the spacer tabs 54, 55, 79 and 80 bent to be parallel to the carton bottom 25. The upward raising or bending of the extensions 81 and 82 automatically folded the corner pieces 103 on themselves on their respective diagonal fold or score 104 so that the actuation of the end walls top wall members, inner wall members and spacer flaps 89 enfolded the same. Just at the time that the end wall inner wall members or panels 88 are brought to their final positions the locking lugs 96 and 97 thereof snapped into the aligned side walls inner wall members elongated perforations 63 and 98 and 64 and 99. The carton is now in the erected position of Figs. 3, 4 and 5.

The modification illustrated in Figs. 6 to 10, inclusive, presents a box or carton which does not have spaced apart wall members or hollow walls but instead utilizes side and end walls that are merely of double thickness. Accordingly the blank illustrated in Fig. 6 includes merely the carton bottom wall or panel 25 from one side of which projects an extension 31' having the panels 67 and 69 which are of substantially the same height and in which the panel 69 is utilized, in part, as the glue flap. The panel 69 has projecting from its ends tucking flaps 76' and 77' which do not have attached thereto the spacer flaps since the end walls, as will presently be made clear, are not of a spaced apart construction but merely double thickness.

Extending from the other side of the carton bottom or panel 25 is an extension 30' comprising merely the side wall outer wall member or panel 38, side wall inner wall member or panel 40 of less height than the outer wall member or panel 38, the platform or panel 41' and the platform side spacing and glue flap or panel 42'. It should be noted that since the side walls are of double thickness the platform 41' is of practically the same width as the carton bottom panel 25. The second side wall inner wall member or

panel 40, similar to the first side wall inner wall member or panel 69 is provided at its ends with tucking flaps 51' and 52' which are devoid of spacer tabs for the same reason that the tucking flaps 76' and 77' do not carry said spacing tabs.

Projecting from the ends of the carton bottom panel 25 are end wall extensions 81' and 82' which are substantially duplicates of one another and comprise merely the end wall outer wall member or panel 86 and end wall inner wall member or panel 88'. The panel 88' is provided with a score or fold line 105 merely for the purpose of ease in inserting the said panel behind the platform as will presently be made clear.

The blank of Fig. 6 after being cut and scored as just described and disclosed in Fig. 6 has adhesive 106 attached to the exposed surface of the side wall outer wall member or panel 67 whereupon the inner wall member or panel 69 is folded on the score or fold line 65 in order to be adhesively secured thereto. Adhesive 107 is applied to the other side wall inner wall member or panel 40 whereupon the side wall-platform extension 30' is folded on the score or fold line 32 thereby superimposing the panel 40 on the panel 38, superimposing platform or panel 41' in part on the panel 38 and on the carton bottom 25 and superimposing the panel 42 on the carton or bottom panel 25 at a point just short of the said carton bottom panel side score 29. The side wall extension 31' is then folded on the score or fold line 29 for bringing the lower or inner end of the side wall inner panel or member 69 into engagement with adhesive 108 on the said spacer-glue flap or panel 42. The blank is now in the folded position of Fig. 7 and in which condition it is shipped to the user.

The user in desiring to set up the box or carton follows substantially the same steps as above merely lifting and raising the carton side wall outer wall members to their normal upstanding positions thereby automatically swinging the platform to a position parallel with the carton bottom and intermediate the height of the carton side walls. It will be noted from Fig. 10 that the said carton platform is anchored to the side walls outer wall members against shifting either upwardly or downwardly. The platform end spacer flaps 58 and 59 are then positioned to have their free ends engage the carton bottom panel 25 thereby support said platform ends.

The end wall extensions 81' and 82' are then folded to have the end wall outer wall members or panels 86 vertically disposed to the carton bottom panel 25 whereupon the inner wall member or panel 88' is folded to lie within the carton having between it and the outer wall member the bellows corners 103 and tucking flaps 51', 52', 76' and 77'. As will be seen from Fig. 9 the said end wall inner wall members 88' extend to the bottom panel or carton base 25 behind the adjacent ends of the platform instead of having the said end wall inner wall members resting on the platform panel as disclosed in Fig. 5.

The modification disclosed in Figs. 11 to 15 is quite similar to the disclosure in Figs. 1 to 5, inclusive, in that the box or carton is provided with walls each of which is formed of spaced apart inner and outer members or of hollow construction. The chief distinction between these constructions is the method of locking the walls in their erected positions and in that the glue flap-side wall extension or panel 44' is of a width that it extends from the carton bottom 25 to its side wall top wall member or panel 39. The side wall extensions 30'' and 31'' are further modified to

the extent of having eliminated from their side wall inner wall members the elongated locking apertures 63, 64, 98 and 99 and in having eliminated from the above noted side wall inner wall members extension-glue flap 44' the slots or notches 61 and 62.

The blank of Fig. 11 is further modified in that its end wall extensions 81'' and 82'' have eliminated therefrom the locking lugs 96 and 97 of the end wall inner wall member or panel 88''. In addition the said panels 88'', each, have extending therefrom a tongue 109 formed by a cut 110 extending into the spacer flap or panel 89. The platform or panel 41 is modified to the extent of having formed near its ends 56 and 57, but inwardly thereof, a U-shape cut 111 which as will presently be made clear, respectively, cooperates with the tongue 109 on each end wall inner wall member or panel 88'' in locking the carton in its erected position.

The blank of Fig. 11 is folded and secured in its folded position, as seen in Fig. 12, in substantially the same manner as above described in connection with the blank in Fig. 1, and it is in this condition that the blank is shipped to the user. The user upon desiring to set up the carton from the blank of Fig. 11 follows the same steps as above described in connection with the carton formed from the blank of Fig. 1 except, instead of snapping locking lugs 96 and 97 into side wall apertures, snaps the locking lugs or tongues 109 into the slits provided in the carton platform by the U-shape cut 111 therein.

As will be seen from Figs. 14 and 15 the platform 41' of the modification is anchored along its sides against any movement while the ends are similarly anchored, downwardly, by the supporting flaps 58 and 59 and, upwardly, by the end walls inner wall members or panels 88''.

In the cartons or boxes heretofore described the platform was held in position by adhesively securing the same to and intermediate the side walls and by providing it with a sub-base or carton bottom panel adhesively secured to the said main bottom panel. In the modification illustrated in Figs. 16 to 20, inclusive, means are provided which do not depend on adhesive for anchoring or securing the parts in position and this modification will now be described.

Accordingly, and as seen in Fig. 16, the blank comprises a panel 112 constituting the bottom or base of the carton having its sides and ends defined, respectively, by score or fold lines 113 and 114 and 115 and 116. Integral with the bottom carton side through the score or fold line 113 is an extension 117 longitudinally divided by score or fold lines 118, 119 and 120, thereby providing in said extension panel 121, in the erected carton forming a side wall outer wall member, a panel 122, forming in the said side wall a top wall member, a panel 123, forming in the side wall an inner wall member, and a panel 124 forming in the carton a glue flap.

Similarly, and connected with the bottom panel 112 through the score or fold line 114 is an extension 125 of greater length than the extension 117 and forming in the erected carton the second side wall and the platform wherefore said extension 125 is divided, longitudinally, by score or fold lines 126, 127, 128, 129 and 130. The said score or fold lines 126 to 130, inclusive, form in the extension 125 the carton second side wall outer wall member or panel 131, a portion of the second side wall inner wall member or panel 132, the platform or panel 133, the spacer for the 75 free end of the platform 133 or panel 134, a sub-

bottom member or panel 135 and a glue flap or panel 136. The ends of the side walls outer wall members or panels 121 and 131 are defined by score or fold lines 137 which integrally hingeably connect thereto corner pieces 138 which are in all respects similar to the corner pieces 103 disclosed in Fig. 1 and constitute bellows corners, for which purpose each of the corner pieces 138 is provided with a diagonal score or fold line 139.

The carton bottom or panel 112 has integrally hingeably connected with its ends through the score or fold lines 115 and 116 similar end walls forming extensions 140 and 141 which are substantially identical with one another wherefore it is deemed sufficient if but one of them be described.

Accordingly, extension 140 is provided intermediate ends with a score or fold line 142 thereby providing a panel 143 which in the erected carton forms the end wall outer wall member and a panel 144 which in the erected carton forms the end wall inner wall member. The ends of the end walls inner wall members are each defined by a score or fold line 145 which integrally hingeably connect thereto the adjacent side of the bellows corner pieces 138.

The first side wall or panel 123 is provided inwardly of its ends with a cut line 146 and 147 thereby providing tongues 148 and 149 integral with and inwardly projecting from the glue flap 124 upon the folding of the side wall panels relative to one another on the score or fold line 120. The platform spacer panel 134 is likewise provided near its opposite ends with cut lines 150 and 151 thereby providing tongues 152 and 153 integral with and inwardly projecting from the sub-base or panel 135 when the second side wall and platform extension 125 is folded on its score or fold lines and particularly when folded on the score or fold line 129.

After the blank of Fig. 16 has been cut and scored as there illustrated adhesive 154 is applied to the carton base or bottom panel 112 for a distance inwardly of its score or fold line 113 and adhesive 155 is applied to the second side wall outer wall member 131 as well as adhesive 156 is applied to the second side wall inner wall member portion or panel 132. At this time the extension 117 has its panel or glue flap 124 turned or folded on the score or fold line 120 onto the panel 123 whereupon the said extension 117 is further folded on the score or fold line 118 thereby bringing the panel 124 into face contact with the adhesive 154.

At this time or simultaneously with the folding of the extension 117 the extension 125 is folded on the score or fold line 129 and then immediately further folded on the score or fold line 126 thereby bringing the glue flap or panel 136 into face contact, on the first fold, with the adhesive 156 and on the second fold with the adhesive 155. The blank of Fig. 16 is now in the condition as illustrated in Fig. 17 whereupon pressure is applied to effectively adhere the parts to one another and it is in this condition that the blank is shipped to the user.

It should be noted that the folding of the extension 117 to its knocked down position projects the tongues 148 and 149 inwardly of the carton and resting on the carton base or panel 112. Similarly the folding of the extension 125 projected the tongues 152 and 153 inwardly of the carton and disposed the same, tongues 152 and 153, respectively on top of the tongues 148 and 149. The user upon desiring to set up the carton does so in substantially the same manner as the

cartons above described were set up, namely, by raising the side walls outer wall members from their flat to their upstanding positions and which operation is illustrated in an intermediate position in Fig. 20. It will be noted from Fig. 20 that the raising of the first side wall or the outer wall member or panel 121 opens or provides openings or apertures 157 in the said side wall inner wall member or panel 123 caused by the cuts 146 and 147 and into which openings the said lugs 152 and 153 of the carton sub-base or panel 135 are projected in the process of erecting the side walls. The upper edge of the openings 157 cooperate with the lugs 152 and 153, after the carton side walls have been erected to their operative positions, in preventing upward movement of the platform or panel 133. The erection of the carton end walls from the blank of Fig. 16 is completed in the same manner that the end walls of the carton of Fig. 8 from the blank of Fig. 6 is effected.

From the foregoing it will be noted that the platform of the carton illustrated in Figs. 16 to 20 is held against displacement vertically of the carton in a manner as effective as that above described where the said carton platform is adhesively secured in position.

The modification illustrated in Figs. 21 to 24, inclusive, is quite similar to that illustrated in Figs. 16 to 20, inclusive, except that instead of interlocking the platform through the sub-base or panel 136 against vertical displacement the said platform is held in operative position by the first side wall resting directly on the platform itself and the modified blank therefor merely consists in effecting a difference in width of the panels thereof.

Accordingly the blank disclosed in Fig. 21 is modified over that disclosed in Fig. 16 by having its side wall inner wall member or panel 123' of less depth than that shown in Fig. 16 and of providing an additional panel 158 between the panels 123' and 124 and which panel 158 forms the first side wall bottom wall member connected with the panel or glue flap 124 through a score or fold line 159. The blank of Fig. 21 is further modified by forming or making the panels 133' and 135' of greater width than the corresponding panels in Fig. 16 and which panels are of substantially the same width as the carton base or bottom panel 112. In the blank of Fig. 21 the cuts 146 and 147 are not formed in the first side wall inner wall member or panel 123' nor are there cuts 150 and 151 formed in the platform spacer or panel 134.

The blank of Fig. 21 is supplied with adhesive in the same manner as the blank of Fig. 16 and is folded to have the parts secured to one another in substantially the same manner as above described wherefore the blank in its knocked down position is as illustrated in Fig. 22 for shipment to the ultimate user.

The erection of the carton of Figs. 23 and 24 from the blank of Figs. 21 and 22 follows the same steps as above described in erecting the carton of Fig. 18 except that the second side wall is substantially completely erected before the first side wall is erected so that the platform may be projected below the said first side wall to have its bottom wall member or panel 158 resting thereon in the final assembly as clearly illustrated in Fig. 23.

It should be understood that the platform of each of the various modifications disclosed in this application may have one or more openings

11

60 therein depending upon the number and contour of the articles to be displayed, packed or shipped as is usual and accepted practice. It should be further noted that in each of the modifications disclosed the knocked down carton or folded blank is in such positions that equal pressure may be applied to the several layers thereof in effecting an adhesion of the parts and panels to one another which is an essential feature in providing a knocked down box or carton to insure the parts being brought to operative positions without breaking the bonds therebetween.

In view of the foregoing it is believed now evident that there has been provided a box or carton which will accomplish the objects initially set forth.

What is claimed is:

1. In a carton of the class described formed of a single blank of card or paper board material comprising a bottom, extensions from two opposed sides of said bottom, one extension being sub-divided into panels to form a side wall including an outer and an inner wall member, the other extension being sub-divided into panels to form a second side wall and platform including an outer wall member, an inner wall member and a platform, said inner wall member being of less height than the outer wall member and spacing one side of said platform upwardly of the bottom, the panels of each of said extensions, respectively, being hingedly connected to one another and to the bottom whereby they may be folded flat on one another for erection by merely raising same from their flat positions, means hingedly interconnecting and interengaging the first side wall and the other side of the platform with one another so that said carton can be knocked down with the side walls inner and outer wall members and platform superimposed on one another and so as to anchor the platform and first side wall against independent upward movement, and extensions from the remaining sides of the bottom for forming end walls.

2. In a carton of the class described formed of a single blank of card or paper board material comprising a bottom, extensions from two opposed sides of said bottom, one extension being sub-divided into panels to form a side wall including an outer and an inner wall member, the other extension being sub-divided into panels to form a second side wall and platform including an outer wall member, an inner wall member and a platform, said inner wall member being of less height than the outer wall member and spacing one side of said platform upwardly of the bottom, the panels of each of said extensions, respectively, being hingedly connected to one another and to the bottom whereby they may be folded flat on one another for erection by merely raising same from their flat positions, means hingedly interconnecting and interengaging the first side wall and the other side of the platform with one another so that said carton can be knocked down with the side walls inner and outer wall members and platform superimposed on one another and so as to anchor the platform and first side wall against independent upward movement, extensions from the remaining sides of the bottom for forming end walls, and spacer flaps extending from the ends of the platform for upwardly spacing the same from the bottom.

3. In a carton of the class described formed of a single blank comprising a bottom, extensions from two opposed sides of said bottom, one ex-

12

tension being sub-divided into panels to form a first side wall including an outer and an inner wall member, the other extension being sub-divided into panels to form a second side wall and platform including an outer wall member, an inner wall member, a platform and a glue flap at the other side of the platform, said inner wall member being of less height than the outer wall member and spacing one side of said platform upwardly of the bottom, the panels of each of said extensions, respectively, being hingedly connected to one another and to the bottom with the glue flap adhesively secured to the first side wall inner wall member for hingedly securing the platform and first side wall to one another whereby the side walls and platform may be folded flat with their panels, respectively, superimposed on the carton bottom for erection by merely raising the side walls from their flat positions, and extensions from the remaining sides of the carton bottom for forming end walls.

4. In a carton of the class described formed of a single blank comprising a bottom, extensions from two opposed sides of said bottom, one extension being sub-divided into panels to form a first side wall including an outer and an inner wall member, the other extension being sub-divided into panels to form a second side wall and platform including an outer wall member, an inner wall member, a platform and a glue flap at the other side of the platform, said inner wall member being of less height than the outer wall member and spacing one side of said platform upwardly of the bottom, the panels of each of said extensions, respectively, being hingedly connected to one another and to the bottom with the glue flap adhesively secured to the first side wall inner wall member for hingedly securing the platform and first side wall to one another whereby the side walls and platform may be folded flat with their panels, respectively, superimposed on the carton bottom for erection by merely raising the side walls from their flat positions, and extensions from the remaining sides of the carton bottom for forming end walls, and spacer flaps extending from the ends of the platform for upwardly spacing the same from the bottom.

5. In a carton of the class described formed of a single blank comprising a bottom, extensions from two opposed sides of said bottom, one extension being sub-divided into panels to form a first side wall including an outer and an inner wall member, the other extension being sub-divided into panels to form a second side wall and platform including an outer wall member, an inner wall member, a platform and a glue flap at the other side of the platform, said inner wall member being of less height than the outer wall member and spacing one side of said platform upwardly of the bottom, the panels of each of said extensions, respectively, being hingedly connected to one another and to the bottom with the glue flap adhesively secured to the first side wall inner wall member for hingedly securing the platform and first side wall to one another whereby the side walls and platform may be folded flat with their panels, respectively, superimposed on the carton bottom for erection by merely raising the side walls from their flat positions, and extensions from the remaining sides of the carton bottom for forming end walls, including, respectively, an inner and an outer wall member hingedly connected to one another, and 75 corner pieces between the side and end walls

outer wall members enfoldable between the end walls inner and outer wall members.

6. In a carton of the class described formed of a single blank comprising a bottom, extensions from two opposed sides of said bottom, one extension being sub-divided into panels to form a first side wall including an outer and an inner wall member, the other extension being subdivided into panels to form a second side wall and platform including an outer wall member, an inner wall member, a platform and a glue flap at the other side of the platform, said inner wall member being of less height than the outer wall member and spacing one side of said platform upwardly of the bottom, the panels of each of said extensions, respectively, being hingedly connected to one another and to the bottom with the glue flap adhesively secured to the first side wall inner wall member for hingedly securing the platform and first side wall to one another whereby the side walls and platform may be folded flat with their panels, respectively, superimposed on the carton bottom for erection by merely raising the side walls from their flat positions, extensions from the remaining sides of the carton bottom for forming end walls, including, respectively, an inner and an outer wall member hingedly connected to one another, corner pieces between the side and end walls outer wall members enfoldable between the end walls inner and outer wall members, and spacer flaps extending from the ends of the platform for upwardly spacing the same from the bottom.

7. In a carton of the class described formed of a single blank comprising a bottom, extensions from two opposed sides of said bottom, one extension being sub-divided into panels to form a first side wall including an outer and an inner wall member, the other extension being subdivided into panels to form a second side wall and platform including an outer wall member, a combined inner wall member and spacer for one side of the platform, a platform and a glue flap at the other side of the platform, the panels of each of said extensions, respectively, being hingedly connected to one another and to the bottom with the glue flap adhesively secured to the first side wall inner wall member for hingedly securing the platform and first side wall to one another whereby the side walls and platform may be folded flat with their panels, respectively, superimposed on the carton bottom for erection by merely raising the side walls from their flat positions, extensions from the remaining sides of the carton bottom for forming end walls, and means hingedly connecting the lower ends of the side walls inner wall members to the carton bottom whereby said side walls inner and outer wall members are each anchored against upward movement and said side walls each has its inner and outer wall members simultaneously swingable on the carton bottom.

8. In a carton of the class described formed of a single blank comprising a bottom, extensions from two opposed sides of said bottom, one extension being sub-divided into panels to form a first side wall including an outer and an inner wall member, the other extension being subdivided into panels to form a second side wall and platform including an outer wall member, a combined inner wall member and spacer for one side of the platform, a platform and a glue flap at the other side of the platform, the panels of each of said extensions being hingedly connected to one another and to the bottom with

the glue flap adhesively secured to the first side wall inner wall member for hingedly securing the platform and first side wall to one another whereby the side walls and platform may be folded flat with their panels, respectively, superimposed on the carton bottom for erection by merely raising the side walls from their flat positions, extensions from the remaining sides of the carton bottom for forming end walls, and means hingedly connecting the lower ends of the side walls inner wall members to the carton bottom whereby said side walls inner and outer wall members are each anchored against upward movement and said side walls each has its inner and outer wall members simultaneously swingable on the carton bottom, said hinge connection between the inner and outer wall members of the first side wall including a panel forming a top wall member having its opposite longitudinal edges respectively hingedly connected to the inner and outer wall members for spacing said inner and outer wall members from one another an appreciable distance.

9. In a carton of the class described formed of a single blank comprising a bottom, extensions from two opposed sides of said bottom, one extension being sub-divided into panels to form a first side wall including an outer and an inner wall member, the other extension being subdivided into panels to form a second side wall and platform including an outer wall member, a combined inner wall member and spacer for one side of the platform, a platform and a glue flap at the other side of the platform, the panels of each of said extensions, respectively, being hingedly connected to one another and to the bottom with the glue flap adhesively secured to the first side wall inner wall member for hingedly securing the platform and first side wall to one another whereby the side walls and platform may be folded flat with their panels, respectively, superimposed on the carton bottom for erection by merely raising the side walls from their flat positions, extensions from the remaining sides of the carton bottom for forming end walls, and means hingedly connecting the lower ends of the side walls inner wall members to the carton bottom whereby said side walls inner and outer wall members are each anchored against upward movement and said side walls each has its inner and outer wall members simultaneously swingable on the carton bottom, the hinge connection of the inner and outer wall members of each of the side walls including a top wall member having the opposite longitudinal edges respectively hingedly connected to the inner and outer wall members for spacing said wall members, respectively, of each side wall, from one another an appreciable distance.

10. In a carton of the class described formed of a single blank comprising a bottom, extensions from two opposed sides of said bottom, one extension being sub-divided into panels to form a first side wall including an outer, an inner and a top wall member for spacing said inner and outer wall members from one another an appreciable distance, the other extension being divided into panels to form a second side wall and platform including an outer wall member, an inner wall member, a platform and a spacer for one side of the platform for spacing said platform upwardly of the bottom, the panels of each extension, respectively, being hingedly connected to one another for articulation whereby the side walls and platform may be folded flat in super-

imposed positions on the bottom for erection by merely raising same from their flat positions, means including cooperating slots and tongues in the first side wall inner wall member and platform spacer for interengagement for anchoring the platform against upward movement, and extensions from the remaining sides of the bottom for forming end walls.

11. In a carton of the class described formed from a single blank of paper or card board material comprising a bottom, extensions from two opposed sides of said bottom, one extension being sub-divided into panels to form a first side wall including an outer wall member, a top wall member, an inner wall member and a glue flap adhesively secured to the bottom, said panels being hingedly connected to one another whereby they may be folded flat, the other extension being sub-divided into panels to form a second side wall and platform including an outer wall member, an inner wall member, a platform, a spacer, a sub-bottom for the platform and a glue flap adhesively secured to the inner surface of its outer wall member, said panels of said other extension being hingedly connected to one another whereby the second wall and platform may be folded flat, means for retaining the platform against vertical movement upon erection comprising slots in the first side wall inner wall member and tongues outwardly projecting from the platform sub-bottom into the slots in the first side wall inner wall member, and extensions from the remaining sides of the bottom for forming end walls.

12. In a carton of the class described formed from a single blank of paper or card board material comprising a bottom, extensions from two opposed sides of said bottom, one extension being sub-divided into panels to form a first side wall including an outer wall member, a top wall member, an inner wall member and a glue flap adhesively secured to the bottom, said panels being hingedly connected to one another whereby they may be folded flat, the other extension being sub-divided into panels to form a second side wall and platform including an outer wall member, an inner wall member, a platform, a spacer, a sub-bottom for the platform and a glue flap adhesively secured to the inner surface of its outer wall member, said panels of said other extension being hingedly connected to one another whereby the second wall and platform may be folded flat, means for retaining the platform against vertical movement upon erection comprising slots in the first side wall inner wall member and tongues outwardly projecting from the platform sub-bottom into the slots in the first side wall inner wall member, extensions from the remaining sides of the bottom for forming end walls, said end walls each including an inner and an outer wall member, and corner pieces between the ends of the side walls and end walls outer wall members adapted to be disposed transversely of the bottom and enfolded by the end walls inner and outer wall members.

13. In a carton of the class described formed of a single blank comprising a bottom, extensions from two opposed sides of said bottom, one extension being divided into panels to form a first side wall including an outer, a top, an inner and a bottom wall member with a glue flap extending from the bottom wall member, the other extension being divided into panels to form a second side wall and platform including an outer wall member, a combined inner wall member and

platform spacer for one side of the platform spacing same upwardly of the bottom, a platform, a spacer for the other side of the platform for spacing said other side of the platform upwardly of the bottom and a platform bottom with a glue flap extending therefrom, the panels of each of said extensions, respectively, being hingedly connected to one another with the glue flaps thereof, respectively, secured to its side wall outer wall member whereby a tubular construction results for each side wall carried by the said side walls outer wall members that, respectively, may be folded flat for erection by merely raising same from their flat positions, extensions from the remaining sides of the bottom and forming end walls, and said tubular constructions upon erection providing means for anchoring the platform against vertical movement.

14. In a carton of the class described formed of a single blank comprising a bottom, extensions from two opposed sides of said bottom, one extension being divided into panels to form a first side wall including an outer, a top, an inner and a bottom wall member with a glue flap extending from the bottom wall member, the other extension being divided into panels to form a second side wall and platform including an outer wall member, a combined inner wall member and platform spacer for one side of the platform spacing same upwardly of the bottom, a platform, a spacer for the other side of the platform for spacing said other side of the platform upwardly of the bottom and a platform bottom with a glue flap extending therefrom, the panels of each of said extensions, respectively, being hingedly connected to one another with the glue flaps thereof, respectively, secured to its side wall outer wall member whereby a tubular construction results for each side wall carried by the said side walls outer wall members that, respectively, may be folded flat for erection by merely raising same from their flat positions, extensions from the remaining sides of the bottom and forming end walls, said first side wall tubular construction having its inner wall member upwardly of the bottom an amount substantially equal to the height of the platform spacer and said platform extending from the second side wall inner wall member to the first side wall outer wall member so that upon erection the platform underlies the first side wall inner and bottom wall members.

15. In a carton of the class described formed of a single blank comprising a bottom, extensions from two opposed sides of said bottom, one extension being divided into panels to form a first side wall including an outer, a top, an inner and a bottom wall member with a glue flap extending from the bottom wall member, the other extension being divided into panels to form a second side wall and platform including an outer wall member, a combined inner wall member and platform spacer for one side of the platform spacing same upwardly of the bottom, a platform, a spacer for the other side of the platform for spacing said other side of the platform upwardly of the bottom and a platform bottom with a glue flap extending therefrom, the panels of each of said extensions, respectively, being hingedly connected to one another with the glue flaps thereof, respectively, secured to its side wall outer wall member whereby a tubular construction results for each side wall carried by the said side walls outer wall members that, respectively, may be folded flat for erection by merely raising same from their flat positions, extensions from the re-

mainning sides of the bottom and forming end walls, said first side wall tubular construction having its inner wall member upwardly of the bottom an amount substantially equal to the height of the platform spacer and said platform extending from the second side wall inner wall member to the first side wall outer wall member so that upon erection the platform underlies the first side wall inner and bottom wall members, the end walls each including an inner and an outer wall member, and corner pieces between the side and end walls outer wall members adapted to be disposed transversely of the bottom and enfolded between the said end walls inner and outer wall members.
